BURNER APPARATUS

Alfred G. Parkes, Toledo, Ohio, assignor to Surface Combustion Corporation, Toledo, Ohio, a corporation of Ohio

Application June 25, 1949, Serial No. 101,331

3 Claims. (Cl. 158—76)

1

This invention relates to combustion apparatus and more particularly to an adapter comprising a slender oil ejecting tube for use with gas burners to permit oil instead of gas to be burned as during severe winter weather when gas is likely to be in short supply.

For a consideration of what I consider to be novel and my invention attention is directed to the following specification and the claims appended thereto.

In the accompanying drawing—

Fig. 1 shows the manner of applying the present invention to a well known type of gas burner to permit oil instead of gas to be burned.

Fig. 2 is an enlarged detail sectional view of the present invention.

Fig. 3 is a view on line 3—3 of Fig. 2.

The gas burner with which the present invention has special utility comprises a burner head 5 having an outlet port 6 which forms in effect the inlet to a refractory combustion tunnel 7 wherein gas with its full complement of air burns to substantial completion before entering the furnace chamber in whose wall 8 the tunnel is ordinarily positioned. The fuel entering the combustion tunnel from the port 6 will ordinarily be ignited by flame issuing from a premix pilot burner 10 mounted on the casting of which the burner head 5 is comprised. The burner head 5 will ordinarily comprise a relatively short tubular extension 11 adapted for connection at its intake end with a pipe 12 which in turn connects with a fuel supply pipe 13 leading from a source of supply of the air-gas mixture which is normally supplied to the burner.

When gas is in short supply the problem is how to switch to oil with minimum trouble and expense. In the present invention this problem is solved by the use of an adapter comprising a relatively slender oil ejecting tube 15 and a supporting head 16 from which the tube extends. As will presently appear, the head 16 is hollow and has separate inlets for oil and a gaseous medium for propelling the oil through the tube 15. A threaded extension 14 on said head permits the latter to be screwed into the outer end of the pipe 12 for support thereby with the tube 15 within the burner head extension 11 to discharge the atomized oil through the burner port 6. The oil propelling medium will ordinarily be air under pressure but the amount of air required for this purpose is only a small proportion of what is required for combustion of the fuel. The additional air required for com-

2

bustion is delivered under appropriate pressure to the burner head extension 11 by a supply pipe which may comprise the pipe 13.

The oil ejecting tube 15 is required to be in line with the burner port 6 but in the absence of special alining means there is no assurance that after the threaded extension 14 of the tube-supporting head 16 has been screwed into the pipe 12 the discharge end of said tube 15 will be in proper alinement with said port 6 as is required for proper functioning of the burner when oil instead of gas is to be burned; hence the primary object of the present invention is to provide in conjunction with the adapter a tube-alining means which shall be well adapted for its intended purpose.

The adapter head 16 is a hollow structure defining a chamber 17 wherein the intake end of the oil ejecting tube 15 is housed to receive the oil and the propelling medium therefor. The chamber has separate inlet apertures 18 and 19 for said oil and propelling medium, respectively. The supply pipe for the propelling medium is indicated at 20, the same having a control valve 21. The supply pipe for the oil is indicated at 22, the same having a control valve 23. The oil inlet proper is defined by a metering nozzle 24 from which the oil issues as a fine spray. The intake end of the tube 15 has a flaring mouth and is close enough to said nozzle to receive all of the oil spray therefrom. The intake end of said tube 15 is in open communication with the chamber 17 hence air entering said chamber from the supply pipe 20 flows directly into the tube for flow therethrough and thereby propels the oil through the tube and through the multiple orifices 25 in the disk 26 which normally closes the discharge end of the tube. The oil issues from the orifices 25 as a fine mist in a carrier stream of air as will now be readily understood.

The structure which defines the tube supporting head 16 is comprised of a base member 28 and a bell type cover 29 removably secured to said member to permit access to the parts within the chamber 17. The base member 28 has a central bore through which the tube 15 freely extends, the bore at its inner end having a spherical seat 27 for a ball 28. A clamping sleeve 29 mounted on the base member 28 is adapted to clamp the ball in adjusted position on said spherical seat. The ball has a tubular stem which at its outer end is adapted to receive a packing nut 31 to provide a fluid tight joint between the tube 15 and the bore of the ball 28 and to releasably hold the tube in position in the bore

of the ball. The normal position of the tube in the ball is such that the mouth of the tube is close enough to the metering nozzle 24 to receive the oil spray therefrom while at the same time permitting unrestricted flow of air to said mouth from the chamber 17. For manufacturing reason the tube 15 will ordinarily consist of two aligned front and rear portions 32 and 33 of which the rear portion has relatively thinner walls than the front portion. The front portion 32 will ordinarily be machined to a standard length whereas the rear portion 33 will be of such length as circumstances may require.

Assuming now that the threaded extension 14 has been screwed tight into the pipe T 12 the procedure to be followed in centering the tube 15 with respect to the burner outlet port is substantially as follows: The bell member 39 is unscrewed from the base member 38 to permit access to the interior of the head 16. The packing nut 31 is released or removed to permit the tube 15 to be withdrawn from the bore of the ball 28. A centering mandrel (not shown) is then inserted in the bore of the ball and extended into the burner outlet 6. The ball clamping sleeve 29 is then screwed tight against the ball to hold it in adjusted position. The mandrel is then withdrawn and the tube 15 reinserted and the clamping nut 31 tightened to hold the tube in proper axial position in the ball and with respect to the metering nozzle 24. The bell member 39 is then screwed back on the base member 38 and the proper connections made with the oil and air supply pipes 22 and 28 as will now be readily understood.

An oil adapter embodying the present invention has the great practical merit of making it possible for even a relatively unskilled workman to quickly align the oil ejecting tube with reference to the burner port 6.

What I claim as new is:

1. In combustion apparatus, in combination, an oil ejecting tube, structure comprising a base member and a bell-type cover therefor conjointly defining a chamber wherein the intake end of the tube is normally housed to receive the oil to be discharged from the tube and to receive a medium for propelling the oil through the tube, the chamber having separate inlets for said oil and said medium, the base member having a bore wherethrough said tube projects out of said chamber, a ball-shape member seated on the rim of the inner end of said bore to form therewith a fluid tight joint, means for adjustably holding said ball-shape member to its seat on said rim, said ball-shape member having a bore wherein said tube is slidably positioned for ready removal therefrom, means providing a fluid tight joint between said tube and said ball-shape member, and the said oil inlet facing the intake end of the

tube in such close relation that oil issuing from the oil inlet as a spray tends to advance directly into the mouth of said tube.

2. In combustion apparatus, in combination, an oil ejecting tube, structure comprising a base member and a bell-type cover therefor conjointly defining a chamber wherein the intake end of the tube is normally housed to receive the oil to be discharged from the tube and to receive a medium for propelling the oil through the tube, the chamber having separate inlets for said oil and said medium, the base member having a bore wherethrough said tube projects out of said chamber, a ball-shape member seated on the rim of the inner end of said bore to form therewith a fluid tight joint and having a stem extending into said chamber, said ball-shape member and its stem having a bore wherein the tube is slidably positioned for ready removal therefrom, means on said stem for holding the tube in adjusted position relative to said ball-shape member, means carried by said base member for adjustably holding said ball-shape member to its seat on said rim, and said oil inlet facing the intake end of said tube in such close relation that oil issuing from the oil inlet as a spray tends to advance directly into the mouth of the tube.

3. In combustion apparatus, in combination, an oil ejecting tube, structure comprising a base member and a bell-type cover therefor conjointly defining a chamber wherein the intake end of the tube is normally housed to receive the oil to be discharged from the tube and to receive a medium for propelling the oil through the tube, said base member having a bore through which said tube projects out of said chamber, a ball-shape member adapted to close the inner end of said bore and having a bore wherethrough said tube slidably extends, means for holding the tube in axially adjusted position in the bore of said ball-shape member, means for holding the ball-shape member in adjusted position against the inner end of the bore of said base member, said chamber having separate inlets for said oil and for said oil propelling medium, and said oil inlet facing the intake end of said tube in such close relation that oil issuing from the oil inlet as a spray tends to advance directly into the mouth of said tube.
